UNITED STATES PATENT OFFICE.

ALBERT CASS, OF MANCHESTER, ENGLAND, ASSIGNOR OF ONE-HALF TO JAMES ROBINSON AND ALFRED ACKROYD, BOTH OF ECCLES, ENGLAND.

PICKING MOTION FOR LOOMS FOR WEAVING.

Application filed July 9, 1927, Serial No. 204,626, and in Great Britain July 15, 1926.

This invention relates to an underpick motion for a loom for weaving of the type in which the picker slides in a slot or groove in the shuttle box bottom and is operated by 5 a depending lever.

According to the present invention the motion is imparted to the depending lever from a rotating disc which carries on its face a cam, wedge or projection adapted to engage 10 at each revolution a runner or roller carried on the end of a lever, the other end of which engages a projecting member or plates on a rod so that an oscillating movement will be imparted to the latter at each revolution of 15 the disc and the movement transmitted to the picker through the depending lever which at its lower end is affixed to the oscillating rod.

The invention will be described with reference to the accompanying drawings:—

20 Fig. 1 is an end view of an underpick loom with the invention applied thereto.

Fig. 2 is a section on line 2—2 Fig. 1.

Fig. 3 is a plan view of lever C¹ carrying the roller C.

25 Fig. 4 is an end view of same.

Fig. 5 is a plan view of the oscillating rod D.

Fig. 6 is a detail of bracket c'.

A rotary disc A is mounted on the tappet 30 shaft A¹ or on a stud or spindle immediately below the driving shaft and is driven through spur or other gearing from a wheel on the driving shaft. A projection B having an inclined, wedge shaped, cam or curved surface is mounted on the face of the disc A, the preferred shape of the projection being as shown 35 in the drawings.

A lever C¹ is carried in a bearing c⁴ so that it can pivot about the frame of the loom and a roller C is carried in a bracket c⁵ on the end of the lever C¹ being held against the face of the disc A so that at each revolution of the latter it will be engaged by the projection B and the lever C¹ moved about its pivot.

45 The other end of the lever C¹ carries a second roller C² which engages with the face of a plate or projection D¹ affixed to a rod D carried in suitable bearings d so that it can oscillate therein. A spring d¹ is affixed at one 50 end to an arm d² extending from the rod D and at the other end is affixed to the frame of the loom and any oscillating movement given to the rod D is against the action of this spring which brings the rod back to its normal position. A projection d³ on the rod D limits the

movement of the latter in the reverse direction.

The depending lever E is forked at its lower end and two members of the forked end pass one at either side of the rod D which is flattened at this point and are pivotally connected thereto by the pin or bolt e so that as the bar D oscillates the lever E will oscillate with it but is at the same time free to move in a direction about its pivot parallel to the bar so that it may follow the movement of the slay G without the mechanism being carried on the slay sword G¹.

The upper end of the vertical lever E is forked to receive the end of the lever or rod E¹ actuating the picker, the other end of this lever or rod E being turned upwards vertically to project through the slot or groove in the shuttle box and engage the picker.

The operation of the mechanism is as follows:—on each revolution of the disc A the projection B engages the roller C and causes the lever C¹ to oscillate about its pivot. This movement causes the roller C² to move over the face of the plate D¹ and move the latter thereby giving a rotary movement to the bar D against the action of the spring d¹ and this motion is in turn imparted to the lever E and from this lever to the lever E¹ actuating the picker. When the projection B has passed the roller D the spring d¹ returns the different parts of the mechanism to their original 80 positions so that the roller C is again in contact with the face of the disc A ready to be actuated by the projection B on the next revolution of the disc.

In order that the driving mechanism of the loom may be rotated in the backward direction for one or more picks when necessary without actuating the picking mechanism, the bracket c' carrying the roller C is loosely mounted on the lever C¹ and is provided with a projection c⁶ which engages the projection c⁷ on the lever C¹ to move the latter when the disc A is rotating in the forward direction but which will allow the roller C to be lifted without moving the lever C¹ when the former is engaged by the projection B when the disc is rotated in the reverse direction.

What I claim as my invention and desire 105 to protect by Letters Patent is:—

1. An underpick motion for a loom for weaving comprising a picker sliding in a slot in the shuttle box bottom, a lever depending therefrom and pivoted to the picker by which 110

- the picker is operated, a rod to which the lower end of the depending lever is affixed, bearings in the frame in which the rod is carried and a projecting plate affixed to the rod, 5 a rotary disc, a tappet shaft on which the disc is mounted, a cam on the face of the disc, a lever pivoted between its ends to the frame one end contacting with the cam, a roller on the other end of the lever to contact with the 10 projecting plate on the aforesaid rod whereby an oscillating movement will be imparted to the latter at each revolution of the disc and the movement transmitted to the picker through the depending lever.
- 15 2. An underpick motion for a loom for weaving comprising a slay sword, a picker sliding in a slot in the shuttle box bottom, a lever depending therefrom and pivoted to the picker by which the picker is operated, 20 a rod to which the lower end of the depending lever is pivoted, bearings in the frame in which the rod is carried and a projecting plate affixed to the rod, a rotary disc, a tappet shaft on which the disc is mounted, a cam on 25 the face of the disc, a lever pivoted between

its ends to the frame one end contacting the cam, a roller on the other end of the lever to contact with the projecting plate on the aforesaid rod whereby an oscillating movement will be imparted to the latter at each revolution of the disc and the movement transmitted to the picker through the depending lever so that it can follow the movement of the slay sword without being connected thereto.

3. An underpick motion for a loom as in 35 claim 1 having the roller actuated by a projection on a bracket loosely mounted on the lever to allow the disc to be rotated in the backward direction without imparting movement to the lever.

4. An underpick motion for a loom for weaving as in claim 1 having a spring against the tension of which the oscillating rod is moved to bring all the parts of the mechanism back to their initial positions after the cam on the disc has passed out of contact with the roller on the end of the pivoted lever.

In testimony whereof I have hereunto set my hand, this 21st day of June 1927.

ALBERT CASS.
